DESIGN FOR A DOOR BUFFER

Emma Gjeruldsen, Brooklyn, N. Y.

Application March 2, 1940, Serial No. 90,637

Term of patent 3½ years

To all whom it may concern:

Be it known that, Emma Gjeruldsen, a citizen of the United States, residing at Brooklyn, in the county of Kings and State of New York, has invented a new, original, and ornamental Design for a Door Buffer, of which the following is a specification, reference being had to the accompanying drawing, forming a part thereof.

The figure is a perspective view of a door buffer showing my new design.

The ornamental features are flush with the surface of the article.

I claim:

The ornamental design for a door buffer, as shown and described.

EMMA GJERULDSEN.
